Application June 18, 1941, Serial No. 398,585

6 Claims. (Cl. 103—138)

This invention relates to rotary compressors, pumps, and the like, of the type employing slideable vanes.

The object of the invention is to provide a rotary compressor or pump having a higher efficiency. More particularly, the object of the invention is to provide a rotary pump or compressor which will deliver a greater volume of fluid under a higher pressure with less power, while at the same time providing an apparatus having a longer useful life. A further part of the major object of the present invention is to provide a rotary pump or compressor which will give a higher volumetric efficiency.

The rotary pump or compressor of the present invention is provided with rigid vanes intended to slide diametrically in operation through the rotor and present its opposite ends for contact with the wall of the chamber within which the rotor is operating. As heretofore constructed, rotary pumps or compressors of such type have rapidly worn the contact edges of the vanes, resulting in considerable slippage of fluid by the vanes, so that such rotary compressors have had the disadvantage of possessing a low efficiency and a relatively short useful life.

I have discovered that these disadvantages can be eliminated and a rotary pump or compressor provided which is capable of operation for long periods of time without appreciable wear of the vanes and without loss of efficiency through slippage of the fluid being pumped by the vanes.

These improvements are attained in accordance with the present invention by certain changes in the shape of the contact surface of the vanes and changes in the contour of the bore of the compressor with which the opposite ends of such vanes are made to contact. These changes are essentially cooperating changes and consist first of the provision of a vane for operation within the bore of the pump or compressor, which vane has contact faces at its ends, each so formed as to contact the bore of the pumping chamber at substantially the leading edge of the vane during the compression portion of the cycle of operation, and so formed as to (in combination with the contour of the bore) transfer its point of contact with the bore rearwardly of the leading edge of the vane during other portions of the cycle of operation of the vane. The explanation for the high efficiency of the rotary pump or compressor of the present invention is thought to reside in the fact that where the point of contact of the vane with the bore of the rotor during the compression portion cycle of operation

is made to occur at substantially the leading edge of the vane, there is little or no opportunity for the pressure of the fluid being pumped or compressed to work under the vane and between its contact face and the bore of the compression chamber. Accordingly, the vane is not wedged by the compression of the fluid being pumped away from the wall of the bore and slippage of fluid by the vane is thereby avoided. In this respect, it is believed that the comparative inefficiency of the more usual type of vane compressors is due to the fact that the vanes employed therein are originally so designed, or in operation wear to a condition, so that their contact with the bore of the compression chamber takes place at substantially the center of the vane, and accordingly the fluid being pumped can exert its pressure towards forcing the vane from tight contact with the bore of the compression chamber.

A further characteristic of the rotary compressor or pump of the present invention is that due to the contact of the vane with its leading edge against the bore of the compression chamber during the compression cycle it appears that satisfactory operation is secured even though the vane may have worn to a point somewhat smaller than the width of the bore to be spanned by the vane, any slippage of fluid by the vane thus taking place on the suction rather than the compression side of the vane. Another characteristic of the rotary compressor or pump of the present invention is such wear as may take place upon the contact face of the vane (which is extraordinarily small) operates to properly shape the contact face of the vane, so as to insure and hold its point of contact with the bore of the compressor during the compression portion of the cycle at substantially the leading edge of the vane.

The foregoing properties and modes of action of the vanes in the rotary pump or compressor of the present invention are dependent not only upon a vane having a proper contact face, but upon the employment in the rotary pump or compressor of a bore in the compression chamber against which the vanes are to contact, which bore has a selected curvature especially designed to permit the aforesaid manner of cooperation between the contact face of the vane and the walls of the bore. The specific nature of the selected curvature of the bore of the pumping chamber of the present invention is difficult to describe in words and will be most fully understood from the hereinafter contained descrip-

tion of the manner of forming or cutting such a bore in the pumping chamber of the rotary compressor or pump of the present invention. The curved surface of the pumping chamber may be considered as divided into two portions—one forming the discharge portion of the pumping chamber, and the other the suction portion of the pumping chamber. In the previous vane type pumps or compressors, such discharge portions and suction portions have been symmetrical, whereas they are made asymmetrical in the pump or compressor of the present invention; the discharge portion of the pump chamber being larger than the suction portion.

The present invention also includes means designed for improving the volumetric efficiency of the pump or compressor. Rotating compressors or pumps of the vane type operate at relatively high speeds. Thus, the peripheral speed of the vanes may be in the neighborhood of 3,000 feet per minute and in excess of the speed at which air or other fluid may be passed through the intake of the compressor or pump. As the vanes pass the end of the suction chamber, a vacuum may be formed behind the vanes, and the volumetric efficiency of the compressor pump is reduced. I have found that the volumetric efficiency of such a rotary pump or compressor may be materially increased by the provision of a suitable pocket in the wall of the pumping chamber, which pocket is located close to the end of the suction chamber of the pump or compressor. This pocket I consider to be acting as an ejection chamber. The fluid handled by the pump or compressor is pressed outward by centrifugal force as the vane approaches the pocket, and ejected from said pocket immediately back of the vane as it passes the pocket, thereby breaking vacuum otherwise there existing, with the result that the volumetric efficiency of the pump or compressor is very materially increased.

The rotary compressor or pump of the present invention also includes certain sealing members associated with the vanes of the compressor designed to improve the efficiency of the pump or compressor by forming an improved seal with the side walls of the pumping chamber.

Various further objects and advantages of the present invention will be apparent from a description of a preferred form or example of a rotary pump or compressor embodying the present invention. For that purpose, I have hereafter, in connection with the accompanying drawings, described one preferred form of the rotary compressor embodying the present invention.

In the drawings:

Figure 1 is an elevation mainly in vertical section.

Figure 2 is a section on the line 2—2 of Figure 1.

Figure 3 is a sectional elevation of the rotor.

Figure 4 is an enlarged diagrammatic view of the curved pumping chamber walls and with the rotor and its vanes therein for the purpose of showing a specific curvature of said bore and its relationship to the rotor and vanes.

Figure 5 is a perspective of one of the vanes.

Figure 6 is a fragmentary section on the line 6—6 of Figure 5.

Figure 7 is a diagrammatic view illustrative of the initial steps employed in forming the curved bore of the pumping chamber.

Figure 8 is a similar diagrammatic view indicative of the final steps in cutting or forming the desired curvature of the pumping chamber.

Figure 9 is a fragmentary view, partially in sec-

tion, of the cutting end of the cutter shown in Figure 7.

Referring to the drawings, the pump or compressor comprises a ring-shaped center casing member 2 and two end casing members 3 and 4. The center casing member 2 and the end casing members 3 and 4 are suitably secured together, as by bolts 5, and are provided with passages to form a continuous water jacket. The end casing member 3 is indicated as provided with a water inlet 6 leading to water passages, such as 7, in the ring-shaped casing member 2, from which return bends, such as 8, in the end casing member 3 and similar water passages carry the water until the water is finally discharged from the water outlet 9 leading from the end casing member 3.

The water thus enters the jacket at the hottest part of the compressor and flows thence to the outlet in such a manner that the heat is taken from the hottest part by the incoming water and carried over the cooler part of the compressor adjacent the intake, whereby the compressor is maintained at a relatively even temperature.

The ring-shaped casing member 2 has a bore 9, the specific shape of which is of particular importance to the invention and will be further described later. Mounted in the bore 9 is a cylindrical rotor 10 of a length substantially equal to the length of the bore. This rotor 10 practically contacts the bore 9 along a theoretical axially extending line at one point 11, preferably at 90° from the bottom of the bore. The rotor 10 is indicated as having certain openings 12 for the purpose of reducing its weight, and another threaded opening 13 for securing suitable end heads 14 and 15 to the rotor 10. The end heads are provided with reduced portions 16 and 17 engaged by antifriction bearings 18 and 19 in the end casing members 3 and 4. A drive shaft 20 extends from the end head 15. Suitable sealing rings 21 and 22 are supported by the end casing members 3 and 4 for making sealing contact with the end heads 14 and 15.

The particular form of machine illustrated is intended to operate as an air compressor and is indicated as having its rotor 10 made up of four segments spaced apart to provide diametrically intersecting slots 23, in which are mounted impeller vanes 24 of a length suitable to maintain their opposite edges in contact with the bore 9 of the ring-shaped casing member 2. While in the particular pump or compressor shown two of such impeller vanes 24 are indicated, one only may be employed, and only a single vane should be employed if the apparatus is to be employed as a liquid pump.

Where two of such vanes are employed, each is provided with an opening 25 leading from one side to the center, as shown in Figure 5, of a suitable width to allow the two crossing vanes to move radially of the rotor relative to each other for the amount necessary. Sealing or compression members 26 for engagement with the flat walls 27 of the end casing members 3 and 4 are inserted in recesses in the sides and ends of the vanes 24 at their leading edges, the sealing members 26 having an enlarged locking head 28 operating to prevent the sealing members from being moved radially outward by centrifugal action. The sealing members 26 are also provided with concave rearward faces 29 at their rear edges to facilitate entrance of compressed air back of the sealing members 26, whereby to force the sealing members laterally outward into

proper sealing contact with the straight walls 27 of the end casing members 3 and 4.

In order to lubricate vanes 24 in a simple and effective manner, the end head 14 is provided with a lubricant feed tube 31 and oil passages 32 in said head to radiate and communicate with the adjacent end of longitudinal oil passages 33 formed in the rotor 18 on opposite sides of and adjacent the slots 23. Outlets 34 from the passages 33 at intervals lead to the walls of the slots.

A pumping chamber is formed, the outer wall of which is formed by the specially shaped bore 9 of the ring-shaped casing member 2 and the straight side walls 27 of the end casing members 3 and 4. The inner wall of the pumping chamber is formed by the cylindrical surface of the rotor 18. The pumping chamber may be considered as divided into two portions—a suction portion and a compression portion; the suction portion lying above the diametric plane passing through the axis of the rotor and the element 11 of the rotor most nearly approaching the bore 9, whereas the compression portion of the chamber lies below such diametric plane. The casing member 2 is indicated as provided with an outlet 35 leading from the compression portion passing out substantially tangential to the bore 9. The casing member 2 is also indicated as provided with a relatively large inlet 36 leading to the inlet portion of the pumping chamber. The outlet passage connects with only a relatively short arc of the discharge portion of the pumping chamber, whereas the inlet passage 36 extends over a considerably greater arc than the suction portion of the pumping chamber. The inlet passage 36 is terminated at a point just preceding the point where in the design of the compressor the centrifugal pressure imparted to the air would otherwise tend to force the air to kick backward into the intake passage. Close to the termination of the intake passage, there is provided a curved transverse pocket 37, which pocket faces towards the direction of movement of fluid in the pumping chamber and is so designed as to catch air thrown outward by the fast-moving vanes 24 as the vanes pass the said pocket and re-direct such air back into the pumping chamber immediately back of the vane as the vane passes the pocket 37, thereby acting as a sort of injection pocket to break the vacuum otherwise existing back of the vane and to help start the flow of air into the pumping chamber, which is otherwise interrupted by the vane passing the end of the inlet to the pumping chamber. As a result, a considerably greater amount of air is thus delivered into the compression portion of the chamber than would be otherwise the case, and the volumetric efficiency of the compressor is accordingly very substantially increased.

In order to best explain the improved curvature applied to the bore 9 of the casing member 2, a description will be given of the method of forming or cutting the desired bore in the casing member 2. For this purpose, reference is, therefore, made first to Figure 7 of the drawings. In forming the desired bore 9 of the casing member 2, the casing member 2 is originally provided with a cylindrical bore, represented by the circle 38, in Figure 7, which circle 38 has a center 39 and a diameter 40. The first step in shaping the cylindrical bore to the desired curvature 9 is accomplished by placing within the casing member 2 a rotor 41, which rotor may be of substantially the same size as the rotor 18 to be included

as a part of the complete compressor. The rotor 41 has a diametrical slot carrying a cutter 42 of a length substantially equal to the diameter of the cylindrical bore 38 now existing in the casing member 2. Originally, the axis of the rotor is made to coincide with the axis of the cylindrical bore 38. The cutter employed is provided with a cutting point 43 located at its leading edge, the cutter being intended to be rotated in the process by the rotor 41 in the same direction as the intended direction of rotation of the vanes of the pump, which direction is clockwise, as viewed in either Figures 1 or 7. The cutter 42 is provided with a contact point 44 on its end opposite from its cutting point, and this contact point is located at the center of the cutter. The cutter is also indicated as preferably provided at its cutting edge with spring-pressed contacts 43a for the purpose of bearing against the bore adjacent the cutting point for holding the cutter against its contact point 44, so that the cutting point will be held away from cutting contact with the bore except where the width of the bore is less than the span of the cutter. Accordingly, the cutter 42, as it is placed within the bore 38, originally contacts the bore at its cutting point 43 and contact point 44, which it will be observed are on a line which does not pass through the center of the rotor. In consequence of this, the subsequent cutting operations will effect an asymmetrical removal of material from the cylindrical bore 38. To initiate the cutting operations, the axis 45 of the cutter is shifted from the axis of the cylindrical bore 38 along a diameter of the bore 38 leading to the point or line at which it is desired to have the rotor most nearly contact finished bore 9 of the casing member. The displacement, indicated in Figure 7, is clearly exaggerated. The movement of the center 45 of the rotor from the center 39 of the cylindrical bore 38 is only sufficient to permit a proper depth cut to be made by the cutter 42. A cut is then made in the bore 38 by the cutter 42 by rotating the cutter 42, the cutter 42 being given suitable axial motion so as to cut or completely ream the bore 38. During this cutting or reaming operation, the cutter 42 is diametrically shifted through the rotor 41 in accordance with the guiding of the cutter 42 by the contact of its guide point 44 with the original cylindrical surface 38, the guide point 44 being of a sufficient width to be guided by the original surface 38 rather than the new cut surface of the bore.

During such initial cutting operation, the original cylindrical bore 38 will be modified in the manner indicated by the dotted line 46. As indicated by the dotted line 46, as the cutting point 43 leaves the horizontal position towards the bottom of the bore, as viewed in Figure 7, it proceeds to remove material from the bore 38 to an increasing depth until it arrives at a vertical position with its cutting point at the bottom of the bore, as viewed in Figure 7, whereafter the depth of the cut will decrease until the cutter is again in substantially the horizontal position. As the cutting point travels upwardly from the horizontal position, it again cuts to an increasing depth until it arrives at substantially a vertical position, after which the depth of the cut again decreases while the cutting point is returning to the horizontal position. The depth at which the cutter cuts while passing downwardly from the horizontal position is considerably more than the depth of the cut made as the cutting point passes upwardly from the horizontal. The removal of

the material takes place mostly at the lower half of the bore, which lower half is to form the compression portion of the pumping chamber.

At two points in the rotation of the cutter, the cutter removes substantially no material from the original bore 38. One of such points is the point where it is desired to have the rotor substantially contact the bore 9 of the casing in the finished pump. The other point, marked 46a, is in advance of the diametric plane through said first point and the axis of the rotor. Thus, the portion of the cylindrical bore 38 that is operated upon by the cutter during its rotation through the upper portion of its cycle is more than 180°, while the portion of the bore operated upon by the cutter during the lower part of its movement, as viewed in Figure 7, is less than 180°.

After the completion of the initial cut, the axis 45 of the rotor 41 is again shifted from the original axis 39 of the original cylindrical bore 38 a suitable distance to allow for taking a further cut, and the cutting operation proceeds as before. The cutting or reaming of the bore is continued in this manner, each time shifting the axis 45 of the rotor 41 along the diametric plane and away from the axis 39 until the axis 45 has been shifted approximately two-thirds of the necessary distance to bring the surface of the rotor 41 in contact with the bore. During each of the subsequent cuts, the diametric shifting of the cutter through the rotor as guided by the guide point 44 of the cutter is regulated by the contact of said guide point on the previous cut form of the bore. As each subsequent cut proceeds, the cutting becomes more and more confined to the portion of the bore below the diametric plane, and particularly the lower left-hand quadrant of the bore, as viewed in Figure 7; to a somewhat lesser extent, the upper left-hand quadrant, as viewed in Figure 7, while the cutter soon begins to miss contact entirely with the bore in the upper right-hand quadrant of the bore, as viewed in Figure 7, and later the lower right-hand quadrant of the bore, as viewed in Figure 7.

After the cutting operation has proceeded in the manner described until the axis of the rotor 41 has been shifted about two-thirds of the intended distance, the remaining cutting operations are performed in the manner indicated in Figure 8. If the operations were continued in the manner described in connection with Figure 7, the final bore cut in the casing member 2 would be of such a shape that no vane of fixed length could maintain itself in contact with the bore during rotation. The final cutting operations are, therefore, performed, as indicated in Figure 8, by a cutter 47. The cutter 47 is indicated as having a cutting point 48 on its leading edge. The guide point 49 of the cutter 47 is, however, shifted so as to be also substantially at the leading edge of the cutter, so that a line passing through the guide point 49 and cutting point 48 will include also the axis 45 of the rotor 41. The cutting operations are continued while the axis 45 of the rotor 41 is shifted along the diametric plane until the axis of the rotor 41 is brought into the intended position of the axis of the rotor 10 in the completed pump. Such subsequent cutting operations bring the bore of the casing member to a shape so that a vane of fixed length may properly contact both of its edges with said bore while it is rotated by the rotor 10. The final cutting operations, however, leave the asymmetrical cut provided by the pre-

vious cutting operations, and accordingly there results a bore 9 of the shape indicated in Figure 4, in which the lower portion of the bore below the horizontal diametric plane, including the axis of the rotor 10, is larger than the upper portion of the bore.

Thus, the original circular bore 38 (Figure 7) is enlarged by the cutting operations so that it becomes generally elliptical due to the removal of portions substantially crescent-shaped in cross section upon the opposite sides of a horizontal plane passing through the axis of the bore 38. Furthermore, the distance along a diametrical plane of the pumping chamber substantially at right angles to said horizontal plane is greater on one side of said horizontal plane than on the other, but in each instance is greater than the radius of the bore 38. The generally crescent-shaped portions removed from the bore are asymmetrical and the greatest radial dimension of the crescent-shaped portion disposed below the aforementioned horizontal plane is approximately twice that of the greatest radial dimension of the crescent-shaped portion disposed above said horizontal plane. Furthermore, the smaller crescent-shaped portion comprises a suction chamber communicating with the inlet 36 and the larger crescent-shaped portion comprises a compression chamber communicating with the outlet 35.

In Figure 4 of the drawings, there is also diagrammatically indicated the rotor 10 of the pump and the vanes 24. The vanes 24 of the pump are indicated as having their contacting ends provided with specially shaped curved contact ends 50. The impeller vanes 24 are made longest at the leading edges of the vanes and relieved slightly rearwardly from the leading edge. When the curvature of the contact ends of the vanes 24 are of the type described and such vanes are working in a bore 9 of the shape previously described, the point 51 of contact between the vanes and bore of the casing member 2 shifts during rotation of the vanes 24. When the vanes are horizontal, as viewed in Figure 4, the point of contact between the left end of the vane and the bore takes place substantially at the leading edge of the vane. As the vane rotates through the initial portion of the suction chamber, the point of contact between the vane and bore 9 shifts rearwardly to the center or beyond the center of the vane. Thereafter, the point of contact of the vane of the bore again shifts forwardly, as indicated in the drawings, and is throughout the compression portion of the movement of the vane close to the leading edge of the vane approaching more nearly the leading edge as it passes to the end of the compression portion of the cycle.

In consequence of the fact that the contact point between the vanes 24 and the bore 9 is at or near the leading edge of the vane throughout the compression stroke, the pressure of the fluid undergoing compression finds little opportunity for forcing the vane away from contact with the bore, and accordingly slippage of fluid by the vane during the compression portion of the cycle is substantially eliminated. It is furthermore found that wearing of the contact ends of the vanes is almost completely eliminated and that any wear which takes place is of a character such as to maintain the proper shape upon the ends of the vanes. Furthermore, it is found that where vanes are worn or initially inserted in a machine of slightly smaller size than

necessary to span completely the bore 9, such vanes will maintain firm contact with the bore 9 during the compression portion of the cycle and allow slippage, if any, to take place at the suction portion of the cycle. This follows from the fact that during the compression portion of the cycle the vane 24 shifts or slides bodily relative to the rotor 10 so that the leading edge of the vane moves in a direction toward said rotor, such sliding movement being resisted by slight but sufficient friction to maintain the leading edge of the vane 24 in contact with the inner curved surface of the bore 9 during said compression portion of the cycle.

For the above reasons, I have found that the rotary compressor or pump of the present invention as distinguished from those heretofore existing has an increased efficiency and is capable of considerably longer life.

While the particular form of rotary compressor or pump herein described is well adapted to carry out the objects of the present invention, it is to be understood that various modifications and changes may be made, and this invention is of the scope set forth in the appended claims.

I claim:

1. A rotary pump or compressor comprising: a housing having a pumping chamber of generally elliptical contour, said housing having an inlet port leading to said pumping chamber and an outlet port leading from said pumping chamber; a rotatable cylindrical rotor within said pumping chamber arranged to contact the wall of said pumping chamber at a predetermined point along a substantially theoretical line extending axially of said pumping chamber, said point of theoretical line contact being disposed between said inlet and said outlet ports; at least one impeller vane carried by said cylindrical rotor and being diametrically slidible with respect to said cylindrical rotor and having ends adapted to contact with the inner wall of said pumping chamber, the dimension of said pumping chamber along a diametrical plane passing through said point of theoretical line contact and the axis of rotation of said cylindrical rotor being approximately equal to the distance between the leading edges of the opposite ends of said vane, and the distance along a diametrical plane of said pumping chamber at right angles to said first-mentioned plane being greater on one side of said first-mentioned plane than upon the other, but in each instance being greater than the radius of a true circle of a diameter corresponding to that of said first dimension, whereby said pumping chamber is enlarged to a greater extent upon one side of said diametrical plane than upon the other and deviates from a true circle by asymmetrical crescent-shaped portions respectively disposed upon opposite sides of said first-mentioned diametrical plane, one of said crescent-shaped portions communicating with said inlet port and the other of said crescent-shaped portions communicating with outlet port.

2. A rotary pump or compressor as defined in claim 1, in which the greatest radial dimension

of one of the crescent-shaped portions is approximately twice that of the greatest radial dimension of the other crescent-shaped portion.

3. A rotary pump or compressor as defined in claim 1, in which the greatest radial dimension of one of said crescent-shaped portions is approximately twice that of the greatest radial dimension of the other crescent-shaped portion, and in which the smaller crescent-shaped portion comprises a suction chamber and communicates with the inlet port and in which the larger crescent-shaped portion comprises a compression chamber and communicates with the outlet port.
- 15 4. A rotary pump or compressor as defined in claim 1, in which one of the crescent-shaped portions extends through a greater arc than the other crescent-shaped portion.
5. A rotary pump or compressor, comprising: 20 a housing including a pumping chamber having a curved wall, said housing having an inlet passage and an outlet passage communicating with said pumping chamber; a cylindrical rotor in said pumping chamber; and an impeller vane carried by said rotor in contact with said curved wall, said housing having an injection pocket formed therein provided with an opening communicating with said pumping chamber, said opening being located beyond but adjacent to 25 the innermost point of mergence of said inlet passage with said pumping chamber, said injection pocket being separated from said inlet passage by said impeller vane in one position of said impeller vane and being adapted to receive fluid forced outwardly by the movement of said impeller vane as it travels past said innermost point of mergence and starts to compress said fluid, said injection pocket being operable to inject said fluid into said pump chamber back of 30 said impeller vane as the trailing edge of said vane passes across the opening of said injection pocket.
- 35 6. A fluid compressor, comprising: a housing including a pumping chamber having a curved wall, said housing having an inlet passage and an outlet passage communicating with said pumping chamber; rotor means in said pumping chamber including an impeller portion in operating contact with said curved wall, said housing 40 having an injection pocket formed therein provided with an opening communicating with said pumping chamber, said opening being located beyond but adjacent to the innermost point of mergence of said inlet passage with said pumping chamber, said injection pocket being separated from said inlet passage by said impeller portion in one position of said impeller portion and being adapted to receive fluid forced outwardly by the movement of said impeller portion 45 as it travels past said innermost point of mergence and starts to compress fluid in said pumping chamber, said injection pocket being operable to inject said fluid into said pumping chamber back of said impeller portion as the trailing 50 part of said impeller portion passes across the opening of said injection pocket.

GORDON R. MEADOR.
